UNITED STATES PATENT OFFICE.

HARVEY GILES, OF BROOKLYN, NEW YORK, ASSIGNOR TO ARTEMAS WARD, OF NEW YORK, N. Y.

COIN-CONTROLLED VENDING MACHINE.

Application filed April 8, 1920. Serial No. 372,491.

To all whom it may concern:

Be it known that I, HARVEY GILES, a citizen of the United States, and a resident of Brooklyn, in the county of Kings and 5 State of New York, have invented certain new and useful Improvements in Coin-Controlled Vending Machines, of which the following is a specification.

The invention pertains more particularly 10 to coin-controlled vending-machines for the sale of confections, and it resides in the novel features, structure and combinations of parts hereinafter described, and particularly pointed out in the claims.

15 The machine of my invention comprises a vertical tray having a series of compartments adapted to receive vertical columns or stacks of the pieces of confection or the like to be sold, an operating handle or rod 20 exposed at its outer end, means operable from said handle in cooperation with introduced coins for ejecting the bottom pieces of confection from the tray, means for directing the sold pieces of confection to an 25 exposed position for removal by the purchaser, means for collecting the proper coins introduced to the machine, such as one cent pieces, and other features which will be hereinafter fully described.

30 Usually the vertical trays provided in coin-controlled vending machines designed for selling pieces of confection have had a series of vertical compartments for holding columns or stacks of the confection, and 35 more frequently these machines have had four of such compartments and the pieces of confection have been so placed in them that their side edges faced frontwardly and rearwardly and were engaged by the ejector 40 means. One feature of my present invention is to provide a machine having six compartments for six columns of the merchandise arranged within the same width that has heretofore been occupied by a tray having 45 four compartments. In carrying out this portion of my invention I so arrange the compartments that the side edges of the pieces of confection extend laterally and that the ejector means engage the ends of 50 said pieces instead of the sides thereof, my ejector mechanism, rendered operative when a coin is present, being adapted for a machine having the merchandise compartments arranged in the manner I have just mentioned.

It has been found that machines of the class to which my invention pertains are so complex and delicate in their mechanisms as to entail considerable loss to the owners for repairs and annoyance to purchasers 60 in the loss of coins introduced to the machine which have become out of order. One object of my invention is to provide a vending machine of the class referred to which will be of such particular construction and durable character as to minimize the necessity 65 for repairs and also minimize the danger of disarrangement of the mechanism by persons violently actuating the exposed operating rod or handle. In carrying out my invention I not only economize space within 70 the exterior casing or cabinet by my particular arrangement of the compartments for the merchandise, but I seek to provide a thoroughly operative and reliable mechanism 75 having but few moving parts, these parts serving to position the introduced coins to be used as coin ejectors and to carry the coins against the bottom pieces of confection in the compartments of the tray, for 80 the purpose of ejecting such pieces from the tray, whence they descend to the purchaser. The details of construction of my machine 85 are such that although I provide a machine having six vertical compartments for merchandise, the casing of the machine requires but three entrance slots for coins, one slot serving for coins for two of the vertical compartments.

The coin-controlled mechanism of my invention comprises various features and details of construction and arrangement, all of which will be better understood from the specific explanation thereof hereinafter presented, with reference to the accompanying 90 drawings, in which:

Fig. 1 is a front elevation, partly broken away, of a coin-controlled vending machine constructed in accordance with and embodying my invention;

Fig. 2 is a vertical section, partly broken away, through the same, taken on the dotted line 2-2 of Fig. 1;

Fig. 3 is a substantially corresponding view illustrating the several removable sections of the machine as separated from the exterior casing or ready to be introduced into said casing, said removable sections consisting of the coin mechanism to be handled as a unit, the coin receiving receptacle 105 located 110

cated below the same, the merchandise tray disposed above said coin mechanism, the lower front door for closing the lower end of the machine, and the upper front portion 5 or door which normally stands at the front of the merchandise tray;

Fig. 4 is a vertical section, partly broken away and on a larger scale, through the lower portion of the machine, taken on the 10 dotted line 4—4 of Fig. 11 and showing all the parts of the mechanism in their normal inoperated position but with a coin shown as having been fed to the machine and become arrested in position for use in ejecting the 15 bottom piece of confection from the compartment of the tray in line with it on the subsequent operation of the machine by an outward pull on the exposed end of the operating rod or handle;

20 Fig. 5 is a corresponding section through a portion of the machine and illustrates the mechanism as having been partly operated and the lower piece of confection as having been partly ejected by the movement of the coin against the end of the same;

25 Fig. 6 is a section corresponding with Fig. 5 but illustrating the mechanism as having been completely operated by the outward pull of the operating rod or handle, the ejected piece of confection being indicated by dotted lines and the coin being indicated as having been released and descending into the coin box;

30 Fig. 7 is a vertical section, partly broken away, through the front portion of the machine, taken on the dotted line 7—7 of Fig. 6 and illustrating the several parts of the mechanism in their operated position, shown in Fig. 6;

35 Fig. 8 is a vertical section, partly broken away, through a portion of the machine, and said section is taken at the front of the tray and on the dotted line 8—8 of Fig. 9;

40 Fig. 9 is a horizontal section through the machine, taken on the dotted line 9—9 of Fig. 4, the mechanism being shown in its normal inoperated position;

45 Fig. 10 is a sectional view corresponding with Fig. 9, but showing the mechanism as having been operated by an outward pull of the operating rod or handle;

50 Fig. 11 is a horizontal section through a portion of the machine, taken on the dotted line 11—11 of Fig. 4;

55 Fig. 12 is a horizontal section through the lower portion of the merchandise tray, shown as empty, the section being on the dotted line 12—12 of Fig. 3;

60 Fig. 13 is a detached rear face view of a hinged plate down which the coins slide from the coin entrance slots to the means for supporting them to serve as goods-ejectors;

65 Fig. 14 is a horizontal section through an upper left hand portion of the mechanism and is presented to illustrate more particu-

larly the mechanism for preventing the entrance of washers to the machine, without interfering with the entrance of proper coins thereto, a coin being shown in position in Fig. 14 as being moved through the coin-slot and by the washer catcher;

70 Fig. 15 is a view partly broken away and partly in section, of certain details, herein-after indentified, serving as a coin gauge and support for the coin during its use as a goods-ejector, and

75 Fig. 16 is a cross-section through a portion of the mechanism at a washer catcher, taken on the dotted line 16—16 of Fig. 14.

80 In the drawings, 30 designates the exterior casing of the machine as a whole, said casing comprising a back 31, sides 32, a top 33, a bottom 34, a lower hinged front door or section 35, and a removable front or door 36.

85 In the rear of the door 36 is formed a chamber for a tray, numbered as a whole 37, for holding the stacks or vertical columns of confections, and within the lower portion of the casing is formed a chamber for the operative mechanism of the machine and also

90 for a coin receptacle 38 which receives the coins after they have left the operative mechanism and from which coins may be removed, when desired, after the front 36 has been removed to free the lower front

95 section 35 so that it may be turned downwardly and forwardly, or to the position shown in Fig. 3, which also shows the coin receptacle 38 as having been withdrawn from the casing of the machine. When in

100 the machine the coin-receptacle 38 rests upon inwardly turned flanges 39 formed at the lower ends of cheek plates 40 secured to the sides 32 of the main casing. At the rear of

105 the coin box or receptacle 38 is provided a chute 41 down which the pieces of confection dislodged from the tray may slide to an opening 42 below the front section 35 of the casing and from which opening said pieces may be removed by hand.

110 The lower front section 35 is preferably of metal and faced on its exterior by a block of wood, as shown, having a recess 43 therein for the fingers of the operator and a slot 44 through which the operating rod or handle

115 45 may be moved forwardly and rearwardly. The metallic portion of the front section 35 is numbered 46, and it has a slot 47 in line with the aforesaid slot 44 through which the operating rod or handle 45 may have its movement. The lower opposite edges of the plate 46 are formed or provided with ears 48 to engage headed pins 49 secured to the sides

120 of the main casing 30, said ears being slotted to pass upon said pins and therewith serve to hinge the front section 35 to the casing, said section being removable, however, by reason of the formation of the slots in said ears 48. The upper end of the plate portion 46 of the front section 35 is bent rear-

125

130

wardly, as shown in Figs. 2 and 4, to close over the operative mechanism of the machine and to afford a shelf receiving the lower edge of the front 36. The side portions of the plate 46 have secured thereto angle iron slotted or recessed plates 50 which, when the lower section 35 is in its upper or closed position, pass upon stud pins 51, as shown in Fig. 4. When the section 35 is in its upper or closed position the face of the plate 46 engages a pin 52 fastened to the front of the coin box 38 and thereby serves to retain said coin box in position between the cheek plates 40.

15 The upper portion of the plate 46 has a bar 53 secured to it, and at the rear of said bar 53 said plate 46 is bent rearwardly to form a horizontal shelf 54 from which the ears 55, two ears being sufficient, extend upwardly to stand substantially parallel with the bar 53. The front 36, when in position, rests upon the shelf 54 and is rigidly held against forward and backward movement between the bar 53 and ears 55. The sides 32 of the main casing are provided in line with the space or opening formed between the bar 53 and ears or lugs 55 with recesses 56 (Fig. 3) adapted to receive the lower side edges of the front 36 and thereby act to lock the lower edge of said front 36 in position, said front when in position serving, by its engagement with the plate 46, to lock the front section or door 35 in closed position. After the front 36 has been moved downwardly into the recesses 56 and upon the seat 54 afforded by the plate 46, said front will, at its upper portion, be pressed inwardly between the sides 32 of the main casing and against vertical shoulders 57 formed thereon, and finally said front 36 will be secured at its upper end to the casing by means of any suitable lock 58, as is customary.

45 The upper portion of the plate 46 is formed with coin entrance slots 59, three of said slots in the present instance being made use of, and one slot being for each two vertical sections or compartments of the main tray 37.

50 The tray 37 has a back and sides, as usual, and also front laterally extending flanges 60 to aid in retaining the stacks of pieces of confection, numbered 61, in position. In the present instance the tray 37 contains six vertical compartments numbered, respectively, 62, 63, 64, 65, 66 and 67, these compartments being arranged in pairs, as shown in Fig. 7, and each pair being separated by a vertical plate 68. The compartments of the tray 37 are narrow, and the pieces of confection 61 placed therein are arranged endwise instead of sideways, the ends of the pieces facing frontwardly and rearwardly, whereby as compared with the usual arrangement of confection in the trays of vending machines, I economize

space, and in the present instance secure six vertical compartments in the width of tray ordinarily affording only four compartments. It is advantageous, outside of the question of economy of space, to arrange 70 the pieces of confection endwise, because thereby the ejector means is enabled to engage a substantial part of the exposed end of the piece to be ejected instead of engaging said piece at the middle of one of its longer 75 side edges. The action is more efficient and less liable to derangement when the ends of the pieces of confection are engaged by the ejector means, than when the side edges of said pieces are so engaged, and this advantage, 80 in addition to the economy of space secured by my invention is quite important.

At the bottom of the tray 37 I provide separated flanges 69, as shown in Fig. 12, 85 to serve as supports for the stacks of pieces of confection 61, and these flanges 69 at their forward portions are recessed out on curved lines, as at 70. The enlargement by the recesses 70 in the flanges 69 permits a coin, facing rearwardly, to pass between the flanges 90 69 until the rear ends of the recesses are reached by a coin, and when the coin passes against the rear edges of said recesses 70, the flanges 69 thereat will cause the coin to be pressed downwardly so that the smaller 95 upper portion of the coin only may pass between the rear parallel portions of said flanges 69. It is desired that the coin shall take a certain position when moved inwardly against the goods to be ejected, and while the coin may always take this position, it is possible that the coin may project upwardly beyond such position to a slight extent, and in this event the edges of the coin would be carried against the rear edges of the recesses 100 70 and be by them depressed to the desired predetermined position, as will be hereinafter explained. The new features about the tray 37 reside in the arrangement of the compartments 62 to 67 inclusive, and in the provision of the recesses 70 in the bottom supporting flanges 69. The tray 37 has one other feature of advantage, and that resides

105 in the provision on the lower front portion thereof of small studs or pins 71, 72, 73, and pins 74, 75. The studs or pins 71 to 75 inclusive project frontwardly, and they are utilized in the manner hereinafter described for deflecting the coins into alignment with the proper compartments in the tray 37 from which the goods are to be sold. A coin introduced through the left hand coin slot 59 will, by the means hereinafter described, be deflected to strike the left hand pin 71 and caused to pass to the position in which I indicate a coin 76 in Fig. 8, said coin being then in position to be used as a means for dislodging the bottom piece of confection from the compartment 62. After the pieces 110 120 125 of confection have been dislodged from the 130

compartment 62, a coin introduced through the left hand coin slot 59 will, with the aid of the pin 71, be positioned in line with the vertical compartment 63 so that the goods 5 may, piece by piece, be sold from said compartment after the compartment 62 has become empty. Coins introduced through the middle coin slot 59 will, by means of the pin 72 be caused to become positioned in line 10 with the vertical compartment 64 until all of the goods therein have been sold, and thereafter said coins will become positioned in line with the compartment 65 for the sale of goods from said compartment. Coins introduced through the right hand coin slot 15 59 will first sell the goods from the right hand compartment 67 and thereafter when that compartment has become empty, be used to effect sales from the compartment 20 66, the pin 73 first deflecting the coins into line with the compartment 67 and thereafter cooperating with other means, deflecting the coins into line with the compartments 66.

Upon the stacks of confection 61 I place 25 weights 77 having forwardly projecting hook-like arms 78. The weights 77 serve to press the pieces of confection downwardly, and when the last piece of confection in any compartment has been sold, 30 the arm 78 of the weight in said compartment will project forwardly of and closely overhang the lower front portion of the tray 37, as I indicate in Fig. 8. The arms 78 cooperate with the pins 71, 72, 73, in 35 deflecting the introduced coins into a position in line with a vertical compartment which has not become empty, and when two adjoining compartments have become empty, the arm 78 of the weights in said two compartments stand in a position to receive an 40 introduced coin, as I indicate by dotted lines at the right hand side of Fig. 8, said coin on the movement of the operating rod or handle 45, being freed to return to the pur- 45 chaser. The pins 74, 75 serve as guards to prevent a coin intended for the compartment 63 or the compartment 66 respectively from becoming positioned in line with the compartment 64 or the compartment 65, re- 50 spectively. The pins 74, 75 serve merely as partitions to confine the coins at the foot of the compartments 63, 66 when the coins are intended to be positioned in those locations. The cooperative action of the arms 55 78 and pins 71 to 75 inclusive will be referred to hereinafter in describing the operation of the machine. At this place it has been intended more particularly to describe the mechanical details connected with 60 the tray.

That portion of the machine which may be designated as the operative mechanism and which is located above the coin receptacle 38 and partly below the upper in- 65 wardly turned portion of the lower front

door 35 and partly below the main tray 37, may be handled as a unit, and this mechanism comprises a stationary main supporting frame numbered as a whole 79, a slidable frame or carriage 80 mounted thereon, a 70 pair of levers 81 loosely connected with said frame or carriage 80 at their outer ends and at their inner ends having a pivotal connection with the main operating rod or handle 45, a hinged shutter plate 75 82 hung at its upper edge from the main frame 79 and a hinged coin-plate 83 hung from its upper end from the upper forward portion of the main frame 79. The carriage 80 is equipped with means, hereinafter de- 80 scribed, for supporting and carrying the coins against the pieces of confection at the bottom of the tray 37, and said carriage 80 has a direct rearwardly and forwardly movement, the movement toward the rear and toward the lower end of the tray 37 being caused by an outward pull on the operating rod or handle 45 and the return movement toward the front of said carriage being caused by two coiled springs 84 whose 90 forward ends are connected to the levers 81, as shown in Fig. 10 and whose rear ends are connected to a stationary member of the main frame 79.

The main frame 79 comprises two corresponding vertical side plates 85 which are connected together at their lower front ends by a plate or bar 86 through which the operating rod or handle 45 passes. The plate or bar 86 has secured to its rear face right angle bracket plates 87 upon which the levers 81 are pivotally mounted, as shown in Figs. 9 and 10. The bar 86 also has secured to it a right angle bracket member 88 which extends rearwardly, as shown in Fig. 4, and is bent upwardly at its inner end to form a stop 89. The body of the operating rod or handle 45 slides on the plate 88, and when said rod or handle is returned inwardly or toward the rear by the springs 84, a shoulder 90 thereon engages said stop 89 and arrests said rod or handle in its predetermined position for subsequent operation. The inner end of the rod or handle 45 guides within a loop 91 secured to the lower side of a stationary bar 92 secured at its ends to the sides 85 of the main frame 79. The inner end of the operating rod or handle 45 is also adapted to slide through an opening 93 formed in a depending rear skirt portion 94 of the main stationary frame 79. The rod or handle 45 carries two pairs of laterally extending upper and lower ears 95, 96, respectively, (Figs. 6 and 7), through which pins 97 extend, and behind the pins 97 are inserted reduced end portions 98 of the adjacent ends of the levers 81, these end portions 98 of said levers being kept against said pins 97 by the tension of the springs 84. The 130

adjoining ends of the levers 81 thus have a bearing against the pins 97, which are rigid with the operating rod 45, and will be pulled outwardly when said rod is pulled outwardly, as shown in Fig. 10 and will be retracted inwardly and drive the rod 45 inwardly when said rod is released and the springs 84 are permitted to operate through the levers 81 to retract said rod. The rod or handle 45 carries an upwardly and rearwardly deflected arm 99 which is rigid with the rod or handle, and at its upper end, when said rod is at its inner position, engages the lower portion of the hinged coin-plate 83, as shown in Fig. 4, and serves to retain said coin plate in its operative position for guiding coins from the coin entrance slots to the means mounted on the carriage 80 for receiving said coins. When the operating rod or handle 45 is pulled forwardly, it carries the arm 99 from engagement with the hinged plate 83 and at that time said plate will turn downwardly by gravity, as shown in Figs. 5 and 6, and release any paper or the like that might have become arrested thereon, anything arrested and then released by the plate 83 being discharged downwardly to the front of the coin-box 38 and finding its way to the discharge opening 42.

The sides 85 of the main frame 79 for the operative mechanism are connected at their lower front ends by the bar or plate 86 hereinbefore referred to, at their upper forward portions by a downwardly and rearwardly inclined plate 100, which is stationary, at their upper rear portion by a downwardly and rearwardly inclined plate 101 which serves to strengthen the frame for the mechanism and as a support for a rod 102 on which the upper edge of the shutter plate 82 is hinged, and at their lower rear portions by a plate 103 which has the downwardly and rearwardly inclined member 94 hereinbefore referred to and a horizontal floor member 104, above which the carriage 80 has its sliding movement and carries the coins fed to the machine.

The shutter plate 82 hinged to the frame member 101 hangs downwardly, as shown in Fig. 4, at the rear of the lower end of the tray 37 and protects the goods in said tray from being interfered with by a wire which might be inserted upwardly along the chute 41. When the machine is in operation and in the act of ejecting a piece of confection, the shutter plate 82 will be by such piece turned rearwardly, as shown in Fig. 5, and after the descent of the ejected piece of confection, as indicated by the dotted lines in Fig. 6, said shutter plate 82 will return to its normal hanging position, shown by solid lines in Fig. 6. The depending member 94 of the rigid frame 103 has an undercut ledge 105 provided on it to aid in catching the

end of a wire which might be inserted upwardly along the chute 41 with the view of dislodging pieces of confection from the tray 37.

One of the more important features of the floor or platform section 104 of the connecting member 103 resides in a special formation thereof and in the provision thereon of vertical stop lugs 106 (Fig. 9), and the formation therein of coin slots 107 down through which the coins finally pass to the coin-receptacle 38, as indicated by the dotted lines in Fig. 6 denoting a descending coin. The floor section 104 is formed with depressions 108 leading to the coin-slots 107 and forming at their forward ends shoulders 109. The forward edge of the floor member 104 is recessed out on curved lines as at 110, as shown in Fig. 10, and said member 104 is concaved between said recesses 110 and the depressions or recesses 108, as at 111, and these recessed portions 110 and 111 are to facilitate the passage of the coins rearwardly over said floor member 104 and against the lower pieces of confection in the tray 37. It may be mentioned that after the coins pass into vertical alignment with the forward ends of the recesses 108, said coins are depressed by their engagement with the edges of the concaved recesses 70 in the flanges 69 at the bottom of the tray 37 so that said coins at their lower edges will enter said recesses 108 and move rearwardly along the same while carried by the coin carrying features connected with the carriage 80 and herein-after described. The purpose of causing the depression of the coins into the recesses 108 is to compel a complete rearward movement of said coins and carriage 80. If, after the handle or operating rod 45 has been started forwardly and the carriage 80 has moved rearwardly far enough to carry the coins to the recesses 108, said handle is released, the springs 84 will start the carriage forwardly and the handle 45 rearwardly and at this time the lower edge of the coins which may be on the carriage will strike a shoulder or shoulders 109 of the recesses 108 and arrest the carriage 80 so that it cannot move forwardly to any great extent under the action of the springs 84. The shoulders 109 thus cooperate with the coins in compelling a full outward stroke of the handle 45 and a complete inward movement of the carriage 80 with each operation of the machine, the coins being held by said carriage 80 until said coins pass into vertical alignment with the coin slots 107, at which time, by the means hereinafter described, said coins are released to descend through said slots and the carriage 80 is permitted to return to its forward position. The forward edges of the slots 107 are preferably formed with saw-teeth 112, which are intended to engage a thread that might be attached to a coin fed 130

to the machine so that said thread may not be utilized in pulling the coin back out of the machine. The teeth 112 are not claimed herein and hence do not require particular description. I have hereinbefore referred to that portion of the floor member 104 which is forwardly of the coin slots 107 and supports the loop 91, as a bar 92, but it is to be understood that the floor member 104 may be in one integral piece, and its forward portion constitute a supporting bar for said loop.

The sides 85 of the mechanism supporting frame 79 have, at their lower portions, studs 113, 114, and these studs are utilized in connection with the cheek pieces 40 for supporting the frame 79 in operative position. The upper edges of the cheek pieces 40 have recesses 115 (Fig. 3) to receive the studs 113 and undercut recesses 116 to receive the studs 114. The cheek pieces 40 support the frame 79 and permit of the removal of said frame whenever necessary through the front lower door-way 25 of the casing 30.

The sides 85 of the frame 79 are formed with recesses 117 which afford seats for lateral flanges 118 provided on the lower opposite sides of the tray 37, the lower end 30 of said tray below said flanges 118 being passed downwardly between said sides 85 so that the flanges 118 on the tray may engage the upper edges of said recesses 117. I may strengthen the sides 85 at the points 35 where they receive the flanges 118 of the tray 37 by securing thereto small bars 119, as shown in Figs. 2 and 3.

The carriage 80 comprises a transverse bar 120 having forwardly bent ends 121 and a bar 122 which is parallel with the main body of the bar 120 and is rigid therewith and spaced rearwardly a distance therefrom slightly greater than the thickness of the coins to be fed to the machine. The end 45 members 121 of the carriage bar 120 are provided with pins 123 which guide in slots 124 formed in the sides 85 of the frame 79, and at their extreme forward ends the end members 121 of said bar 120 are connected 50 with the said sides 85 by means of screws 125 which extend through the aforesaid slots 124 and cooperate with the pins 123 in guiding the carriage 80 in its rearward and forward movements. The screws 125 also 55 cooperate with the forward ends of the slots 124 in affording stops for arresting the carriage 80 in its normal forward position adjacent to the tray 37, to which position said carriage is moved by the springs 84 and 60 which springs, in cooperation with said stops, yieldingly hold said carriage in its said position. The end members 121 of the bar 120 extend downwardly and then turn 65 toward each other forming brackets or ears 126 (Fig. 10) on which are rigid pins 127

which extend between the jaws of the slotted outer ends of the levers 81, said jaws and pins serving to freely connect said levers with the carriage 80. When the operating rod or handle 45 is pulled forwardly from its position shown in Fig. 9, it will act through the levers 81 and pins 127 to force the carriage 80 rearwardly, as shown in Fig. 10, and when the rod or handle 45 is released, after a sale, the outer ends of the levers 81 acting through the pins 127 and themselves actuated by the springs 84 will return the carriage 80 forwardly to its initial position, the handle or rod 45 at the same time returning rearwardly to its initial position.

The body member of the bar 120 has forwardly projecting ears 128, and these ears have secured to their lower side by means of screws 129 a coin gauge bar 130 which has slotted ears 131 below said ears 128 and adapted for sliding movement on said screws 129. The plate 130 serves as a coin gauge plate and as a support for the coins carried inwardly by the carriage 80, and said plate 130 has fingers 132 which project through the body of the bar 120 and also through the bar 122 and stand in line with the stops 106 formed on the floor member 104 of the rigid frame 103, the purpose of said fingers being, when the carriage 80 is moved rearwardly, to engage said stops 106 and thereby before the carriage 80 comes to rest, force the coin gauge and supporting plate 130 forwardly so as to release the coins and permit them to descend through the coin slots 107. The plate 130 is connected with leaf-springs 133 which normally act to keep the plate 130 close up against the bar member 120 or in the position shown in Fig. 9, 100 but which when the handle 45 is pulled forwardly and the fingers 132 are arrested by the stops 106, yield sufficiently to permit said plate 130 to be separated from the bar 120 far enough to release the coins. When 105 the carriage 80 again starts forwardly, the springs 133 will restore the plate 130 to its initial relation to the bar 120, said plate 130 then being in position to support coins fed between said bar 120 and the bar 110 122.

The bar 122 carried by the bar 120 of the carriage 80 has secured against its opposite rear ends and at intermediate points, small plates 134, one of which is shown on an enlarged scale in Fig. 15. The plates 134 are fastened to the bar 122 by means of screws 135 which pass through slots in said plates 134, as shown in Fig. 15, so as to render said plates adjustable. The plates 134 each carries at its outer end a forwardly projecting finger 136 which has an outwardly diverging face or is inclined forwardly and outwardly. The fingers 136 of the plates 134 form coin gauges and supports for cooperation with 125 130

rearwardly inclined edges 137 on the coin supporting and gauge plate 130, said plate 130 having at its ends two of said rearwardly inclined or converging edges 137 and at its middle portion two rearwardly inclined or converging edges 137. The space between one of the fingers 136 and the adjacent edge 137 on the plate 130 constitutes a space less in diameter than that of a proper 10 coin fed to the machine, so that said coin may rest on the inclined edge of the finger 136 and the adjacent inclined edge 137 of the plate 130. The inclined edges of the fingers 136 and the inclined edges 137 on the 15 plate 130 will permit a coin of too small diameter for the machine to slip by them, while a coin of proper diameter will be retained and supported by the cooperating finger 136 and adjacent edge 137. In the present 20 instance, as shown in Fig. 10, I provide spaces for six coins between fingers 136 and inclined edges 137, there thus being one coin space for each vertical compartment in the tray 37. The coins supported on the 25 inclined edges of the fingers 136 and the plate 130 and between the bars 120 and 122 are carried rearwardly on the movement of the carriage 80 against the lower pieces of confection in the tray 37 and finally descend 30 through the coin slots 107 hereinbefore described. The plate 130 serves for cooperation with all of the fingers 136 on the plates 134 for supporting the coins fed to the machine preparatory to said coins being moved 35 rearwardly by the carriage 80.

The carriage 80 thus comprises the bar 120 having forwardly extending ends 121, the bar 122, which is parallel with the body of the bar 120 and properly spaced rearwardly 40 therefrom, the small gauge plates 134 secured against said bar 122 and each having the coin supporting finger 136, the coin gauge plate 130 and the springs 133 normally keeping the plate 130 against the bar 120 and 45 yieldingly permitting said plate 130 to move forwardly when the fingers 132 on said plate are pressed against the stops 106 on the platform or floor 104, the forward movement of said plate 130 serving to release the coins 50 to descend by gravity through the coin slots 107.

The coin-plate 83 is hinged at its upper end on pivot screws 138 to the upper forward corners of the frame 79, and said plate 55 has a rearwardly convexed face and in the normal position of the parts of the machine, the lower edge of said plate 83 is directly over the space between the bars 120 and 122 of the carriage 80. The purpose of the plate 60 83 is to direct the coins introduced to the machine to the space between said bars 120, 122 so that they may fall upon the supporting fingers 136 and inclined edges 137 of the plate 130. The plate 83 is shown in its normal position in Fig. 4 and in the positions it

assumes during the movement of the operating rod or handle 45, in Figs. 5 and 6. The plate 83 is held in its normal position by the arm 99 carried by the operating rod or handle 45, and when said handle 45 is pulled forwardly, in the operation of the machine, the plate 83 swings downwardly by gravity.

In Fig. 4 I illustrate a coin, which I number 139, as having descended down the plate 83 and become supported between the bars 75 120, 122. The coins which reach the plate 83 are introduced through the coin slots 59 and between the upper edge of said plate 83 and the adjacent edge of the stationary plate 100, which also serves to guide the 80 coins downwardly and confine them against said plate 83. The plate 83 is shown in front elevation in Fig. 7 and in rear elevation in Fig. 13. At its upper rear corners the 85 plate 83 is formed with downwardly and inwardly inclined flanges 140 which serve to deflect the coins introduced through the outer or end coin slots 59 inwardly and downwardly so that said coins may finally strike the pins 71, 72, 73, respectively, on 90 the lower forward portion of the tray 37 and be by them deflected into the proper spaces between the bars 120, 122 for the respective compartments of the tray 37. It may be seen on reference to Fig. 4 that in 95 its normal position the lower portion of the plate 83 is adjacent to the lower front face of the tray 37. The plate 83 is cut away to form openings 141, and above these openings the plate 83 is provided with magnets 142 100 which serve to arrest steel disks which may be fed to the machine in lieu of coins. When a steel disk is fed to the machine and the handle 45 is pulled forwardly, the plate 83 turns downwardly and the steel disk 105 will be jarred from the magnets and descend forwardly of the coin box. At the bottoms of the openings 141 I form rearwardly projecting curved lips 143 which serve to aid in directing steel disks and the like, on the 110 downward movement of the plate 83, forwardly through the openings 141. The openings 141 and lips 143 are also of advantage in allowing any foreign matter which may have become arrested on the 115 plate 83 to escape through said openings, thereby keeping the face of the plate 83 clear and unobstructed. Upon the front face of the plate 83 is secured a rod 144 upon 120 which are hung a series of weight testers 145, these weight testers all being alike and consisting of weighted dogs of known character having their lower ends projected through recesses or slots 146 formed in said plate 83. When a coin of proper weight 125 is fed to the machine, it will descend against one of the weight testers 145 and tilting said weight tester will pass on downwardly to the coin supports between the bars 120, 122. If a coin too light in weight should 130

be fed to the machine, it will not actuate the weight tester 145 and will be deflected from the true path for coins of proper weight. The weight testers 145 are not separately claimed herein, since weight testers of this general character are familiar in this art.

Upon the upper front edge of the plate 83 I provide washer catchers for preventing a washer introduced through a coin-slot from passing downwardly over the plate 83. I provide one washer catcher for each coin entrance slot 59, and said washer catchers are all alike and are clearly illustrated in Figs. 7 and 14. Each washer catcher mechanism comprises a slidable plate 147 held against the plate 83 by screws 148 which pass through slots in said plate 147, this rendering the plate 147 slidable. One end of the plate 147 is provided with a pin 149 which projects through a slot in the plate 83 and normally stands in the path of a coin which may be fed through the coin slot and against said pin and against a stationary pin 150 also secured to said plate 83. The space between the pin 149 and the stationary pin 150 is less than the diameter of a proper coin to be fed to the machine, and hence when a coin is fed to the machine between said pins 149 and 150, the coin will press the pin 149 laterally so as to widen the space between it and the pin 150. The other end of the plate 147 has an ear 151 to which is pivoted a pointed dog 152 having a short arm 153 which is engaged by a spring 154. The tendency of the spring 154 is to project the pointed end of the dog 152 through a recess or hole 155 in the plate 83, this action of the spring 154 taking place when the pin 149 and plate 147 are slid in a direction from said spring 154, thereby placing a tensin on said spring and carrying the dog 152 to a position in which its pointed end may pass through said hole 155. In Fig. 13 I show the pin 149 in its normal position, while in Fig. 14 I illustrate the operated position of said pin and the plate 147, said pin and plate having been moved by the introduction of a coin which, in Fig. 14, I number 156. When the coin 156 is introduced between the pins 149, 150, it forces the pin 149 and plate 147 to the left and positions the dog 152 to project its pointed end through the hole 155 and against the coin. The coin 156 being a proper coin, may be pressed on downwardly between the plates 83 and 100 and be caused to slide down said plate 83 to operative position. If a washer had been introduced between the plates 83, 100 in lieu of the coin 156, the dog 152 would project its pointed end through the hole in the washer and prevent the downward movement of the washer. The dog 152 is what may be called a washer catcher, and the upper side of the pointed end of said dog

will be flat so as to prevent a washer being pressed downwardly beyond it while on its lower surface the pointed end of said dog may be beveled upwardly so as to permit of the withdrawal of a washer from the coin slot of the machine, as shown in Fig. 16.

I have hereinbefore described all of the mechanical details of the machine and many of the movements of the several parts thereof during the operation of the machine. The pieces of confection will be placed in the tray 37 endwise so that the ends of said pieces may project forwardly and rearwardly, respectively, and in this instance I provide six compartments for the stacks of 80 confections. The tray 37 is seated upon the general frame 79 for the coin mechanism and projects downwardly between the sides of said frame, and in the position of said tray 37 with respect to the other features presented, the pins 71 to 75 inclusive on the front lower portion of said tray project toward and rather close to the lower portion of the coin-plate 83, as shown in Fig. 4. When a coin is fed through, for instance, the left hand coin slot 59 it will slide down the plate 83 and striking the pin 71 on the tray will be deflected to the position between the bars 120, 122 in which I indicate a coin 76 in Fig. 8. Thereupon the operating rod or handle 45 will be pulled outwardly, and this will result in the carriage 80 being moved rearwardly and in carrying said coin 76 against the lower piece of confection in the left hand compartment, causing said piece to move rearwardly against the shutter plate 82 and finally descend to the chute 41 as indicated by the dotted lines in Fig. 6. The coin 76 carried at the left hand end of the bars 120, 122 and supported upon the inclined finger 136 and inclined edge 137 thereat (Fig. 15) will move against the left hand curved recess 110 in the platform 104 and be caused to ride upon said platform and along one of the grooves or recesses 111 therein. The movement of the coin 76 over the front edge of the table or platform 104 serves to slightly elevate the coin from the coin-gauge edges between the bars 120, 122, and then after the coin has passed to the left hand recess 108, the coin is intended to descend by gravity and enter said recess, so as to cooperate with the front shoulder 109 thereof in preventing reverse movement of the carriage 80. If the coin should not fall by gravity into the recess 108, it will be assisted in such movement by the upper edge of the coin being carried against the curved edges of the recesses 70 in the flanges 69 at the bottom of the tray 37, and hence if for any reason the coin should not automatically lower into the said recess 108 so as to operate as a dog for preventing reverse movement of the carriage 80, it will be forced downwardly into said recess by its engagement 120 125 130 135 140 145 150 155 160 165 170 175 180 185 190 195 200 205 210 215 220 225 230 235 240 245 250 255 260 265 270 275 280 10020 10025 10030 10035 10040

with the edges of the aforesaid recesses 70 in the flanges 69. The continued rearward movement of the coin carried by the carriage 80 results in the lower piece of confection 5 being ejected from the left hand compartment 62, as will be understood without further description. All of the coins fed through the left hand coin slot 59 will pass to the position of the coin 76, shown in Fig. 10 8, until all of the goods in the compartment 62 have been sold and the weight 77 has descended to carry its arm 78 downwardly to a position nearly in vertical line with the pin 71. When the arm 78 is in this position, 15 with the compartment 62 empty, it prevents the pin 71 from deflecting a coin introduced through the left hand slot 59 into position at the foot of the compartment 62 and cooperates with said pin in deflecting any 20 coins then introduced through the left hand coin slot 59 to a position at the foot of the tray compartment 63, all of the coins fed through the left hand coin slot 59 reaching such position at the foot of the tray column 25 63 until that column has become exhausted of its merchandise. After that any coins fed through the left hand coin slot 59 would fall upon both arms 78 and, upon the outward movement of the coin plate 83, would 30 fall downwardly at the front of the coin box and be returned to the purchaser.

All coins fed through the middle coin slot 59 will pass down the plate 83 and striking the pin 72 on the tray, will be deflected to position at the bottom of the compartment 64 until said compartment becomes empty of its contents, and thereafter the arm 78 of the weight 77 belonging to the compartment 64, having descended to 35 its lower position, any further coins introduced through the middle coin slot will be by said arm and the pin 72 deflected to position at the foot of the compartment 65 so as to sell the goods from that compartment. 40 Coins introduced through the right hand coin-slot 59 will be deflected by the pin 73 to position below the compartment 67 until all the goods have been sold from said compartment, and thereafter any further coins 45 introduced through the right hand coin-slot 59 will be by the arm 78 of the weight for the compartment 67, in connection with the pin 73, directed to position at the foot of the compartment 66, so that the goods in 50 said compartment 66 may be sold. When all of the goods in the compartments 66, 67 have been sold, an introduced coin would become arrested on the two arms 78 of the weights belonging to said compartments, as 55 I indicate in Fig. 8 by dotted lines, and this coin, on the forward pull of the handle 45, would be returned to the purchaser. It is not necessary that I should provide the pin 60 71, 72, 73 for deflecting the coins to definite 65 positions for one compartment or another,

but I prefer to provide said pins so that all of the goods of one compartment shall be sold before the sales commence of the goods from the next adjoining compartment. Each pair of the compartments will contain 70 the same character of goods. As hereinbefore mentioned, the pins 74, 75 serve mainly as partitions to prevent the jumping of the coins laterally from position at the foot of the compartments for which they are intended. The arms 78 on the weights 77 co-operate with the pins 71, 72, 73 in properly directing the coins to position at the foot of the respective compartments and said arms perform no other duty. 75

It is desirable that when the handle 45 is pulled outwardly, the coin slide plate 83 should turn downwardly into as nearly as possible a vertical position so that any paper or other matter which might have 80 been stuffed through the coin entrance slots and become arrested thereon may fall therefrom, and to this end I provide in the coin guide plate 100 a series of holes 170 (Fig. 11) to afford any necessary clearance for the 85 upper inner edges of the coin guide pins 149, 150 when said plate 83 does turn downwardly.

I have hereinbefore described the particular details of the machine presented as embodying my invention, but I do not wish to be limited to all of the details of form and construction shown and described, since I am well aware that many of these details may be modified within the spirit of my 90 invention. 95

What I claim as my invention and desire to secure by Letters Patent, is:

1. In a coin-controlled vending machine having coin entrance slots, a vertical tray 105 for holding columns of pieces of the merchandise to be sold and an exposed operating handle, in combination, a horizontally slideable carriage provided with means for supporting coins on edge and facing the lower pieces of merchandise in said columns, stops for arresting said carriage in its normal forward position adjacent to said tray and to receive the introduced coins, a pair of pivoted levers connected at their outer 110 ends with said carriage and at their inner ends with said handle, a spring normally holding in cooperation with said stops, said carriage at its said forward position adjacent to said tray, and means for releasing 115 said coins on the operation of the machine, said levers at their outer ends serving when said handle is pulled outwardly to force said carriage rearwardly to carry the coins against and dislodge the lower pieces of 120 merchandise, and said spring serving to restore the said levers, handle and carriage to their normal position after each sale. 125

2. In a coin-controlled vending machine having coin entrance slots, a vertical tray 130

- for holding columns of pieces of the merchandise to be sold and an exposed operating handle, in combination, a horizontally slidable carriage operable from said handle, means on said carriage for receiving and releasably supporting coins on edge and facing the lower pieces of merchandise in said columns and to be moved against and dislodge said pieces when the carriage is operated from said handle, means for retiring a lower support carried by the carriage from and thereby releasing said coins on the operation of the machine, and means to be engaged by said coins on a reverse action of said carriage before completing its full stroke for locking said carriage against reverse movement and comprising a platform over which said coins are moved and which has recesses to receive the lower edges of the coins and shoulders at the forward ends of said recesses to be engaged by the coins on such reverse action of the carriage.
3. In a coin-controlled vending machine having coin entrance slots, a vertical tray for holding columns of pieces of the merchandise to be sold and an exposed operating handle, in combination, a horizontally slidable carriage operable from said handle, means on said carriage for receiving and releasably supporting coins on edge and facing the lower pieces of merchandise in said columns and to be moved against and dislodge said pieces when the carriage is operated from said handle, means for retiring a lower support carried by the carriage from and thereby releasing said coins on the operation of the machine, and means to be engaged by said coins on a reverse action of the carriage before completing its full stroke for arresting the carriage and comprising a platform over which said coins are moved and which has upwardly inclined surfaces to slightly elevate the coins, longitudinal recesses into which the lower edges of the coins may thereafter descend and shoulders at the forward ends of said recesses to be engaged by the coins on such reverse action of said carriage.
4. In a coin-controlled vending machine having coin entrance slots, a vertical tray for holding columns of pieces of the merchandise to be sold and an exposed operating handle, in combination, a horizontally slidable carriage operable from said handle, means on said carriage for receiving and releasably supporting coins on edge and facing the lower pieces of merchandise in said columns and to be moved against and dislodge said pieces when the carriage is operated from said handle, means for retiring a lower support carried by the carriage from and thereby releasing said coins on the operation of the machine, a platform over which said coins are moved and which has longitudinal recesses to receive the lower edges of the coins and shoulders at the forward ends of said recesses to be engaged by the coins to arrest the carriage on any reverse movement thereof before it has completed its full operative stroke, and means for engaging the upper edge of the coins during their travel and compelling the coins to enter said recesses.
5. In a coin-controlled vending machine having coin entrance slots, a vertical tray for holding columns of pieces of the merchandise to be sold and an exposed operating handle, in combination, a horizontally slidable carriage operable from said handle, means on said carriage for receiving and releasably supporting coins on edge and facing the lower pieces of merchandise in said columns and to be moved against and dislodge said pieces when the carriage is operated from said handle, means for retiring a lower support carried by the carriage from and thereby releasing said coins on the operation of the machine, a platform over which said coins are moved and which has longitudinal recesses to receive the lower edges of the coins and shoulders at the forward ends of said recesses to be engaged by the coins to arrest the carriage on any reverse movement thereof before it has completed its full operative stroke, and means for compelling the coins to enter said recesses comprising shoulders formed by enlargements in facing edges of the bottom of the tray, said shoulders standing in the path of the upper edge of the coins and acting to force the coins during their travel downwardly into said recesses in rear of said shoulders.
6. In a coin-controlled vending machine having coin entrance slots, a vertical tray for holding columns of pieces of the merchandise to be sold and an exposed operating handle, in combination, a horizontally slidable carriage provided with means for receiving and carrying introduced coins on edge and facing the lower pieces of merchandise in said columns, stops for arresting said carriage in its normal forward position adjacent to said tray and to receive the introduced coins, a pair of horizontally disposed pivoted corresponding levers normally extending on rearwardly converging lines and at their inner adjacent ends being connected with said handle and at their outer ends with the opposite sides of said carriage, and a spring normally holding, in cooperation with said stops, said carriage adjacent to the front of said tray and said levers in their said normal position, said levers at their outer ends serving when said handle is pulled outwardly to force said carriage rearwardly to carry the coins against and dislodge the lower pieces of merchandise, and said spring serving to

restore the said levers, handle and carriage to their normal position after each sale.

7. In a coin-controlled vending machine having coin entrance slots, a vertical tray having side by side compartments for holding columns of pieces of the merchandise to be sold and apportioned to the respective coin slots, and an exposed operating handle, in combination, a horizontally slideable carriage operable from said handle, means on said carriage for releasably supporting coins on edge and facing the lower pieces of merchandise in said columns and to be moved against and dislodge said pieces when the carriage is operated from said handle, means for releasing said coins on the operation of the machine, means for directing the coins from said slots to said coin supporting means, means for deflecting the coins entered at one slot to the foot of one of said columns until all the pieces therein have been sold and means automatically positioned by the exhaustion of said column for then deflecting the coins entered at said slot to the foot of another column for the sale of pieces therefrom.

8. In a coin-controlled vending machine having coin entrance slots, a vertical tray having side by side compartments for holding columns of pieces of the merchandise to be sold and apportioned to the respective coin slots, and an exposed operating handle, in combination, a horizontally slideable carriage operable from said handle, means on said carriage for releasably supporting coins on edge and facing the lower pieces of merchandise in said columns and to be moved against and dislodge said pieces when the carriage is operated from said handle, means for releasing said coins on the operation of the machine, means for directing the coins from said slots to said coin supporting means, and means adjacent to said supporting means for deflecting the coins entered at one slot to the foot of one of said columns until all the pieces therein have been sold and then to the foot of another column for the sale of pieces therefrom, said coin deflecting means comprising pins projecting forwardly from the lower end of the tray and arms on weights supported on the columns of merchandise and passing to position to serve as coin deflectors when lowered by the dislodgement of the pieces of merchandise.

9. In a coin-controlled vending machine having coin entrance slots, a vertical tray for holding columns of pieces of the merchandise to be sold and an exposed operating handle, in combination, a horizontally slideable carriage operable from said handle, means on said carriage for releasably supporting coins on edge and facing the lower pieces of merchandise in said columns and to be moved against and dislodge said pieces

when the carriage is operated from said handle, means for releasing said coins on the operation of the machine and means for directing the coins from said slots to said coin supporting means, said coin supporting means comprising two parallel bars separated by a space between which the coins pass, stationary transverse pins to be engaged by one edge of the coins and a movable bar having projections extending transversely of said space to be engaged by the other edge of the coins, and said movable bar being spring pressed to yieldingly maintain its said projections in normal position across said space, and said means for releasing the coins comprising stationary lugs, and fingers on said movable bar to be carried against said lugs for arresting said bar during the travel of said carriage.

10. In a coin-controlled vending machine having coin entrance slots, a vertical tray for holding columns of pieces of the merchandise to be sold and an exposed operating handle, in combination, a horizontally slideable carriage operable from said handle, means on said carriage for releasably supporting coins on edge and facing the lower pieces of merchandise in said columns and to be moved against and dislodge said pieces when the carriage is operated from said handle, means for releasing said coins on the operation of the machine and means for directing the coins from said slots to said coin supporting means, said coin supporting means comprising two parallel bars separated by a space between which the coins pass, plates adjustably secured on one of said bars and carrying transverse pins to be held in stationary position across said space and to be engaged by one edge of the coins, a movable bar supported on said carriage and having projections extending transversely of said space to be engaged by the other edge of the coins and a spring yieldingly holding said projections in normal position across said space, and said means for releasing the coins comprising stationary lugs, and fingers on said movable bar to be carried against said lugs for arresting said bar during the travel of said carriage.

11. In a coin-controlled vending machine having coin entrance slots, a vertical tray for holding columns of pieces of the merchandise to be sold and an exposed operating handle, in combination, a horizontally slideable carriage operable from said handle, means on said carriage for releasably supporting coins on edge and facing the lower pieces of merchandise in said columns and to be moved against and dislodge said pieces when the carriage is operated from said handle, means for releasing said coins on the operation of the machine and means for directing the coins from said slots to said

- coin supporting means, said coin supporting means comprising two parallel bars separated by a space between which the coins pass, transverse pins to be engaged by one edge of the coins, a movable bar having projections extending transversely of said space to be engaged by the other edge of the coins and a spring yieldingly maintaining said projections in normal position crossing said space, and said means for releasing the coins comprising means for arresting said movable bar during the travel of the carriage whereby the coins are carried from said projections.
12. In a coin-controlled vending machine having coin entrance slots, a vertical tray for holding columns of pieces of the merchandise to be sold and an exposed operating handle, in combination, a horizontally slidable carriage operable from said handle, means on said carriage for releasably supporting coins on edge and facing the lower pieces of merchandise in said columns and to be moved against and dislodge said pieces when the carriage is operated from said handle, means for releasing said coins on the operation of the machine and means for directing the coins from said slots to said coin supporting means; said coin supporting means comprising two parallel bars separated by a space between which the coins pass, stationary pins extending transversely of said space and having inclined edges to be engaged by one edge of the coins, a movable bar having projections with inclined edges extending across said space to be engaged by the other edge of the coins and a spring normally maintaining said movable bar with its projections crossing said space.
13. In a coin-controlled vending machine having coin entrance slots, a vertical tray for holding columns of pieces of the merchandise to be sold and an exposed operating handle, in combination, a horizontally slidable carriage operable from said handle, means on said carriage for releasably supporting coins on edge and facing the lower pieces of merchandise in said columns and to be moved against and dislodge said pieces when the carriage is operated from said handle, means for releasing said coins on the operation of the machine, means for directing the coins from said slots to said coin-supporting means, and a platform over which said coin supporting means travel and which is provided with slots through which said coins may descend when released so to do, said coin supporting means comprising parallel bars separated by a space between which the coins pass and transverse members crossing said space to be engaged by opposite edges of the coins, and said means for releasing the coins comprising means for moving one set of said members from the coins so as to leave the coins unsupported.
14. In a coin-controlled vending machine having coin entrance slots, a vertical tray for holding columns of pieces of the merchandise to be sold and an exposed operating handle, in combination, a horizontally slidable carriage operable from said handle, means on said carriage for releasably supporting coins on edge and facing the lower pieces of merchandise in said columns and to be moved against and dislodge said pieces when the carriage is operated from said handle, means for releasing said coins on the operation of the machine, and means for directing the coins from said slots to said coin supporting means and comprising a stationary downwardly inclined plate, a hinged downwardly inclined plate to cooperate with said stationary plate and adapted to swing downwardly into substantially vertical position when the machine is operated and means connected with said operating handle for restoring said hinged plate to its normal position at the conclusion of the operation of the machine and on the return of said handle to its normal position.
15. In a coin-controlled vending machine having coin entrance slots, a vertical tray for holding columns of pieces of the merchandise to be sold and an exposed operating handle, in combination, a horizontally slidable carriage operable from said handle, means on said carriage for releasably supporting coins on edge and facing the lower pieces of merchandise in said columns and to be moved against and dislodge said pieces when the carriage is operated from said handle, means for releasing said coins on the operation of the machine, and means for directing the coins from said slots to said coin supporting means and comprising a stationary downwardly inclined plate, a hinged downwardly inclined plate to cooperate with said stationary plate and adapted to swing downwardly into substantially vertical position when the machine is operated and means connected with said operating handle for restoring said hinged plate to its normal position at the conclusion of the operation of the machine and on the return of said handle to its normal position, and said hinged plate having adjacent to its upper end pairs of coin-directing pins between which the coins pass from said coin slots and one pin of each pair being spring pressed toward the other pin of the pair.
16. In a coin-controlled vending machine having coin entrance slots, a vertical tray for holding columns of pieces of the merchandise to be sold and an exposed operating handle, in combination, a horizontally slidable carriage operable from said handle, means on said carriage for releasably supporting coins on edge and facing the lower pieces of merchandise in said columns and to be moved against and dislodge said pieces

- when the carriage is operated from said handle, means for releasing said coins on the operation of the machine, and means for directing the coins from said slots to 5 said coin supporting means and comprising a stationary downwardly inclined plate, a hinged downwardly inclined plate to cooperate with said stationary plate and adapted to swing downwardly into substantially vertical position when the machine is operated and means connected with said operating handle for restoring said hinged plate to its normal position at the conclusion of the operation of the machine and on the return of 10 said handle to its normal position, and said hinged plate having openings therein through which foreign material may pass to and descend from the front side thereof, thereby avoiding the clogging of the machine.
17. In a coin-controlled vending machine having coin entrance slots, a vertical tray for holding columns of pieces of the merchandise to be sold and an exposed operating 25 handle, in combination, a horizontally slideable carriage operable from said handle,
- means on said carriage for releasably supporting coins on edge and facing the lower pieces of merchandise in said columns and to be moved against and dislodge said pieces 30 when the carriage is operated from said handle, means for releasing said coins on the operation of the machine, means for directing the coins from said slots to said coin supporting means and comprising a stationary downwardly and inwardly inclined plate, a downwardly inclined plate to cooperate with said stationary plate hinged at its upper end and adapted to swing downwardly by gravity into substantially vertical position when the machine is operated, and means connected with said operating handle for normally maintaining said hinged plate in operative position and adapted to restore said plate to its normal 35 position at the conclusion of the operation of the machine and on the return of said handle to its normal position.
- Signed at New York city, in the county of New York and State of New York, this 50 27th day of March, A. D. 1920.
- HARVEY GILES.
